[57] CLAIM

The ornamental design for a scraping device adapted for accepting an elongated handle, as shown and described.

DESCRIPTION

FIG. 1 is a perspective view of a scraping device adapted for accepting an elongated handle, wherein the elongated handle is shown in dotted lines for purposes of illustration;

FIG. 2 is a top plan view thereof;

FIG. 3 is a side elevational view with the opposite side being a mirror image thereof;

FIG. 4 is a bottom plan view thereof;

FIG. 5 is a front elevational view thereof; and,

FIG. 6 is a rear elevational view thereof.

FIG. 2

FIG. 3

FIG. 4

FIG. 5

FIG. 6
